DELIVERY SHEET SLOW DOWN MECHANISM

Henri E. Peyrebrune, River Forest, Ill., assignor to Miehle-Goss-Dexter, Incorporated, Chicago, Ill., a corporation of Delaware

Application May 24, 1957, Serial No. 661,469

4 Claims. (Cl. 271—79)

This invention pertains in general to delivery mechanisms for sheet fed printing presses or the like sheet processing machines. It is directed more specifically to an improved sheet slow down device for effectively retarding each sheet upon its release by the grippers of an endless chain conveyor for deposit onto a delivery pile.

Heretofore it has been customary to utilize suction rollers and/or suction fingers to engage each sheet at its rear end or front edge respectively as it is released from the grippers of the delivery chain conveyor in order to retard and deposit the sheet onto the delivery pile. Such means have proven to be satisfactory and quite efficient in operation when relatively light weight paper is processed and when the press is operated at moderate speeds. When heavier weight stock such as cardboard or the like is handled, however, the inertia of such relatively heavy sheets tends to overcome the effectiveness of the vacuum devices and, as a result, the sheets cannot be stacked accurately. Moreover, the failure of the vacuum devices to effectively retard the sheets results in their striking the front stops or joggers with such force that the leading edge thereof invariably becomes damaged to such an extent that the sheets are rendered unacceptable. This condition obviously becomes more acute as the speed of the press and/or the weight of the sheets is increased.

To overcome this condition it has already been proposed to provide positive acting mechanical means for engaging each sheet upon its release by the chain delivery grippers whereby it is retarded and accurately positioned on the delivery pile. Such a device is disclosed in U.S. Patent 1,080,036. The device disclosed in said patent however, is relatively limited in its operation, due to the drive mechanism employed, and would be comparatively ineffective on modern sheet fed presses in which the lineal speed of the sheets is usually in excess of 500 feet per minute. Under such circumstances the ratchet driven retarding roller of the patented device would quickly be accelerated to substantially the same speed as the sheets and thus would have little effect insofar as retarding the sheets is concerned.

It is a primary object of this invention, therefore, to provide an improved mechanical sheet slow down device which will effectively retard the forward motion of sheets regardless of press speed.

Another object is to provide a positively driven sheet slow down device incorporating resilient means which permit limited over travel of the retarding member to avoid damaging the sheets.

A still further object of this invention resides in the provision of means whereby the coating members can be adjusted in accordance with the thickness of the sheets being processed.

A further object resides in the provision of means for adjusting the slow down unit longitudinally in the path of the sheets in accordance with the size of the sheets being handled.

A still further object resides in the provision of novel drive mechanism for the unit whereby the coating mem-

2

bers thereof remain in timed relation with respect to the chain delivery mechanism when longitudinal adjustments are imparted thereto.

Still another object resides in the provision of means for controlling the trailing portion of the sheet until it is engaged by the retarding members.

Other objects and advantages will become apparent from the following description when read in conjunction with the accompanying drawings wherein:

10 Figure 1 is a schematic view in side elevation showing the slow down unit as embodied in a conventional double pile delivery mechanism;

Figure 2 is a sectional view of the device in front elevation shown at an enlarged scale;

15 Figure 3 is an end view as seen from the left of Figure 2 with parts broken away to illustrate the drive mechanism;

Figure 4 is a view taken along line IV—IV of Figure 2;

20 Figure 5 is a view similar to Figure 4 illustrating the sheet control disc;

Figure 6 is a sectional view taken along lines VI—VI of Figure 3;

25 Figure 7 is a fragmentary sectional view showing how the friction band is mounted on the brake shoe segment; and

Figure 8 is a section along VIII—VIII of Figure 7.

As shown in Figure 1, the sheet retarding unit is illustrated, merely by way of example, as embodied in a double pile chain delivery mechanism and, although it has particular advantages when used in conjunction with such device, this is not to be regarded as a limitation since it will produce equally effective results when used in conjunction with a conventional single pile delivery mechanism.

30 As shown in the drawing, the chain delivery mechanism comprises a pair of spaced endless chains 10 which are tracked around sprockets 11 and 12 and have fixed thereto in spaced relation a plurality of gripper units 13 for taking successive sheets from the last impression cylinder of the printing press, not shown, and conveying them over the respective delivery piles 14 and 15. As the respective gripper units approach the position above either one of the delivery piles, the gripper actuating levers 16 associated therewith engage one or the other of the gripper actuating cams 17 or 18, whereupon the gripper elements are opened and the sheet is released for deposit onto the respective pile. Depending upon the manner in which the sheets are to be deposited or delivered the cams 17 and 18 may be so set so that all of the sheets may be delivered onto either one of the piles 14 or 15 or they

40 may be arranged to be actuated so that each alternate sheet is deposited upon its respective pile. The alternate method of delivery is particularly advantageous when it is necessary to provide more time to dry the ink impression on each sheet before the next subsequent sheet is deposited thereon.

45 As each sheet is released by the chain delivery grippers, its forward motion continues until its leading edge strikes against the front jogger blades 19 whereupon it is stopped abruptly and allowed to settle onto the pile. As was mentioned hereinbefore, modern sheet fed rotary presses operate at relatively high speed and thus it will be apparent that unless the sheets are adequately controlled and retarded upon their release from the chain delivery grippers, they are apt to strike the front jogger blades 19 with such force that the leading edge thereof becomes damaged to such an extent that the sheets are rendered unacceptable. Heretofore, it has been the practice to provide suction rollers adjacent the rear edge of the delivery pile to engage and effect a retarding influence upon the sheets as they are released by the delivery grippers. Such devices have proven to be only moderately successful. When light stock is processed for example,

50

55

60

65

70

the trailing edge thereof flutters and waves in such an erratic manner as it is being conveyed by the chain delivery grippers that the suction roller seldom, if ever, makes sufficient contact therewith to have any material retarding effect. The inertia of heavy stock such as cardboard or the like, on the other hand, is so great as to completely overcome any retarding effect provided by the known suction devices.

With the present invention each sheet is retarded by positive acting mechanical means which engage both the top and bottom surfaces of the sheets, preferably on each side thereof near its tail edge, simultaneously with or immediately prior to its release by the delivery grippers whereupon the sheet is immediately and positively retarded. Moreover, the coating sheet engaging members of the unit are adapted to impart final motion to the sheet whereby to position it accurately onto the pile.

Each sheet slow down unit is mounted adjacent the rear edge of its respective delivery pile, see Figure 1, and is comprised of side frame members 21 and 22, Figure 2, which are located in spaced relation on each side of the delivery mechanism. These frame members, in turn, are supported on a pair of spaced horizontally disposed bars 23 and 24 which are an integral part and extend substantially the full length of the chain delivery mechanism.

A shaft 26 which extends transversely across the full width of the delivery mechanism, is journaled for rotation in the side frame members 21, 22, above the path of the sheets in bearings 27 and 28 which in turn are mounted in eccentric brackets 29 and 30 respectively. At one end the shaft 26 is provided with an internal gear 31, which latter is securely keyed thereto and held in position by a cap 32 and screw 33 which is threaded into the end of the shaft.

Mounted substantially vertically below the shaft 26 is a second shaft 34 which also is journaled in the side frame members 21 and 22 for rotation about an axis below the path of the sheets and this shaft is also provided with a drive gear 36 which is secured to one end thereof.

The two shafts 26 and 34 are driven in precise timed relation directly from the delivery chain 10 by means of a chain sprocket 37. The latter meshes with the lower run of the chain 10 which at this point is supported on a track 38 secured to the innerface of the bar 23. The sprocket 37 is fixed to a shaft 39 which is journaled for rotation in the side frame member 21 and has secured to its opposite end a compound pinion gear 41 having teeth 42 which mesh with the teeth of the drive gear 31 and gear teeth 43 which mesh with the teeth of the drive gear 36. Thus it will be seen that when the delivery chain 10 is in operation the respective shafts 26 and 34 will be rotated in opposite directions and in timed relation therewith.

Mounted on the shaft 34 for engagement with the bottom face of the sheets passing thereover are a pair of wheels 44. The latter are preferably keyed to the shaft for positive rotation therewith and are adjustable axially thereon so that they can be positioned in accordance with the width of the sheets being delivered. Set screws 46 are provided in the hub of each wheel so they may be locked in any selected position. Mounted on the shaft 26 for coaction with each of the wheels 44 to retard the sheets as they pass therebetween is a semi-cylindrical brake shoe segment 47 and a coating sheet control disc 48. As best shown in Figure 2, the control disc 48 is secured by means of screws 51 to the end face of a collar 52 which is keyed to the shaft 26 for rotation therewith. The brake shoe segment 47 on the other hand is rotatably mounted on the collar 52 and is retained in position thereon by the flange 53 formed integral with said collar and the washer 54 which is secured to the opposite end of the collar 52 by means of screws 56. As in the case of the wheels 44, this collar and therewith the control disc and brake shoe segment is also adjustable axially

on the shaft 26 whereby to locate the respective members laterally in accordance with the size of the sheets being processed so that they will engage these sheets within the unprinted margins thereof.

5 The brake shoe segment 47 is arranged to be driven in unison with the shaft 26 by the control disc 48 which latter is provided on its innerface with a laterally projecting block 57. This block is secured to the control disc by means of screws 58 and is adapted to engage a corresponding block 59 fixed to the adjacent face of the brake shoe segments. Thus as the disc 48 rotates in clockwise direction, as seen in Figure 5, the brake shoe segment will be positively driven in unison therewith. It will be appreciated that the ratio of the respective drive 10 gears is such that the surface speed of the brake shoe segment 47 and its coating wheel 44 will be substantially one half the lineal speed of the chain conveyor 10 so that when engaged by the respective members, the sheets will be materially retarded before being deposited onto the piles. A coil spring 61, located in the U shaped cavity 62 formed in the brake shoe segment 47, exerts a constant pressure between the end 63 of said cavity and the block 57 on the control disc to thereby maintain the blocks 57 and 59 in intimate contact.

20 25 To provide the friction required for retarding and controlling the sheets upon their release by the chain delivery grippers, the brake shoe segment is equipped with a friction band or tire 64 which may be formed from any suitable material such as pure rubber or the like which has a high coefficient of friction but will not mark the sheets upon engagement therewith. This tire, which is substantially square in cross section, see Figure 8, is adapted to fit into a groove 66 formed in the cylindrical surface of the brake shoe and it extends about the entire cylindrical 30 portion of the shoe with the ends thereof secured to the radial reinforcing ribs 67 and 68 by the screws 69. Thus it can readily be removed for replacement if it becomes worn or damaged.

35 Obviously, the entire length of the tire 64 is not utilized at any one given time to retard the sheets. In other words only a relatively short section of the periphery of the tire actually engages the sheets to retard them and such contact is preferably near the trailing edge of the sheet. Therefore, as will be evident from 40 Figure 4, when the tire 64 is seated in the groove 66, its peripheral surface is spaced from the coating surface of the wheel 44 and only a small portion thereof is projected beyond the normal radius for coaction with the wheel 44. In order to project a portion of the tire 45 beyond its normal radius a shim 71 is inserted beneath the tire 64, said shim being seated on the shoulder 72 provided therefore in the periphery of the brake shoe segment 47. This shim may be of any desired length depending upon the extent of contact required upon the 50 sheet and it may be positioned angularly about the periphery of the brake shoe to thereby time the engagement of the tire with the sheets. Such contact is preferably timed so that the rear edge of the sheet will be engaged immediately prior to its release by the chain 55 delivery grippers so that adequate control of the sheets will be maintained at all times.

55 In order not to tear or in any other way damage the sheet during the short period of time when it is engaged by the chain delivery grippers and the coating slow down members which, as stated hereinbefore, have a surface speed substantially one half that of the delivery grippers, provision is made for the brake shoe to advance with respect to its coating drive members until the sheet is released by the chain delivery grippers. As 60 stated hereinbefore the brake shoe segment 47 is driven by the control disc 48 through the coating blocks 57, 59 and these blocks are maintained in contact by the resilient pressure of spring 61. Thus when the active portion of the tire 64 engages the sheet 73 while the leading edge of the latter is still gripped by the delivery grip-

pers, see Figure 4, the brake shoe can advance momentarily with the sheet against the progressively increasing tension of the spring 61, as evidenced by the gap 74 between the blocks 57 and 59.

Upon release of the sheet by the delivery grippers it will immediately be retarded to the peripheral speed of the slow down members which will impart final motion to the sheet to deposit it on the pile. Upon continued rotation of the slow down members the projecting portion of the tire 64 will move out of contact with the coating wheel 44 whereupon the tension of spring 61 will return the brake shoe segment to its original position with the stop 59 in contact with the coating stop 57.

The provision of the resilient coupling between the brake shoe and the sheet control disc is particularly advantageous because it obviates the need for critical time consuming adjustments of the shim 71 which otherwise would be required in order to time the engagement of the tire 64 with the sheet precisely as its leading edge is released by the delivery grippers.

This feature is also of particular advantage when the device is used in conjunction with a double pile delivery mechanism as illustrated herein, and especially when the alternate method of delivery is employed. At such time it will be evident that each alternate sheet must be retarded by the slow down unit associated with the rear pile 14 for deposit thereon whereas the intervening sheets must be permitted to pass through the slow down unit for deposit on the front pile 15. The resilient connection between the brake shoe and the control disc permits such sheets to pass through the rear slow down unit for deposit on the front pile without the need for expensive and complicated tripping mechanism which otherwise would be required to trip the rear unit to an inoperative position as the alternate sheets pass therethrough.

Although the primary purpose of the sheet control disc 48 is to drive the brake shoe segment in timed relation therewith, it also serves to control the trailing portion of the sheets until they are engaged by the slow down members. It will be appreciated that when the sheets are being conveyed by the chain delivery grippers 13, the tail edge thereof is relatively free and tends to flutter and wave in an erratic and unpredictable fashion. Unless this erratic action is adequately controlled the sheet is very apt to move out of its normal path and thus will not be engaged by the sheet slow down members.

For this reason, the sheet control disc 48 is made substantially continuous with a radius such that its peripheral surface is substantially tangent to the path of the sheets. Thus as the gripper bars 77 move under the shaft 26, see Figure 5, the edge of the control disc comes down over the sheet to restrain it against excessive fluttering until it is engaged by the tire 64 on the brake shoe. In order to provide clearance for the delivery chain gripper bar 77 the control disc is provided with a notch or recessed portion 78 as clearly indicated in Figure 5. The control disc also serves as a protective cover for the brake shoe segment 47 preventing foreign material and dust from collecting in the coil spring cavity and around the coating stops which would have an adverse effect upon the efficient operation thereof.

The shaft 26 also is adjustable vertically relative to the shaft 34 whereby to vary the contact relation between the tire 64 and the wheel 44 in accordance with the thickness of the sheets being processed and to compensate for any wear of the respective tire 64. This adjustment is accomplished by means of the eccentric brackets 29 and 30, see Figures 2 and 3, which are adjustable angularly in the respective frame members 21 and 22. Each bracket is formed with a radial arm 81, the free end of which is bifurcated and carries a pivot pin 82. The latter is provided with a tapped hole transverse to its axis to receive the threaded end of a horizontally disposed screw member 83 which is rotatably mounted in a block 84 pivotally secured to the inner face of the respective

frame members 21 and 22. Collars 86 and 87 which are pinned to the screw 83 on each side of the block 84 prevent axial movement thereof when the latter is rotated by means of the handle 88 to impart corresponding rotary motion to the brackets. The extent of adjustment imparted to the respective brackets is limited by the stop nuts 91 which are pinned in predetermined spaced relation on the screw 83. Thus it will be apparent that upon rotation of the screw 83 the eccentric brackets 29 and 30 will be angularly displaced about the axis of the shaft 26 to thereby raise or lower said shaft relative to the shaft 34 within maximum and minimum limits. The teeth of the respective gears 36 and 43 are formed so that they will remain in mesh through the full range of adjustment and continued to drive the slow down members in precise timed relation. This adjustment also makes it possible to raise the brake shoe member of the rear unit of the double pile delivery mechanism to an inoperative position when all of the sheets are to be delivered to the front pile 15.

In the device as illustrated in Figure 1, the respective jogger blades 19 and gripper actuating cams 17 and 18 are mounted in relatively fixed position and, therefore, when sheets of different sizes are to be processed it is necessary to adjust the slow down units longitudinally in the path of the sheets in accordance with the sheet size.

The mechanism whereby such adjustment can be accomplished is best illustrated in Figures 3 and 6 wherein it will be seen that a shaft 92 is journaled for rotation in the respective side frame members 21 and 22 and carries a pair of pinion gears 93 which are secured thereto and positioned so as to engage rack teeth 94 formed in the lower edge of the supporting bars 23 and 24. Thus when the shaft 92 is rotated by means of the handle 96 the slow down units will be moved longitudinally in the path of the sheets in either direction and to any extent required. The units are locked against any unintended movement while the press is in operation by means of the locking screw 97 which is threaded into a tapped opening provided therefore in the frame member 21 so as to engage the shaft 92.

It will be noted that when such longitudinal adjustments are imparted to the slow down unit, the rotary members, i.e., the control disc, the brake shoe and the coating wheels 44, will remain in timed relation with the chain delivery due to the fact that these members are driven directly from the chain 10 through the drive sprocket 37 and thus will be rotated accordingly when the units are moved relative to the chain 10. This is important in view of the fact that the control disc must clear the respective gripper bars and thus the notch 78 provided therein for this purpose must be maintained in the proper position.

While I have herein described and illustrated a preferred embodiment of my invention it will be apparent that various changes and modifications can be made without departing from the spirit of this invention and which I intend to cover in the appended claims.

I claim:

1. In a sheet delivery, the combination of mechanism for retarding sheets upon their release from the grippers of a sheet conveyor comprising, a pair of rotatable members mounted respectively above and below the path of the sheets, drive means for rotating said members at reduced surface speed with respect to said conveyor, said members being adapted to engage each sheet momentarily and, upon its release by said grippers, to retard its forward motion, and resilient means interconnected between one of said members and said drive means to permit said one member to advance with respect to said drive means upon initial engagement with said sheet.

2. In a sheet delivery, the combination of mechanism for retarding sheets upon their release from the grippers of a sheet conveyor comprising, a wheel mounted for ro-

tation below the path of the sheets, an arcuate member rotatably mounted above the path of the sheets and having coaction with said wheel to engage each sheet and retard it upon its release by said grippers, supporting shafts for said wheel and said member, drive means for rotating said shafts and therewith said wheel and said member at reduced surface speed with respect to said conveyor, and resilient spring means interconnected between said member and its supporting shaft to permit overtravel of said member with respect to said drive means and said wheel upon initial engagement with the sheet.

3. In a sheet delivery, the combination of mechanism for retarding sheets upon their release from the grippers of a sheet conveyor comprising; a pair of horizontally disposed bars having racks formed in their lower edges, a frame member slidably mounted on each bar, an arcuate member mounted for rotation on a shaft above the path of the sheets, a coacting wheel mounted for rotation on a shaft below the path of the sheets, means for journaling said shafts in said frame members including eccentric journals for the shaft of said arcuate member, manually operable means for rocking said eccentric journals to thereby vary the contact relation between the arcuate member and the wheel, drive means interconnected with said conveyor for rotating said arcuate member and said wheel at reduced surface speed with respect to said conveyor whereby upon engagement of a sheet between the arcuate member and the wheel its speed is retarded, resilient means interconnecting said arcuate member with said drive means to permit overtravel of said arcuate member relative to said drive means under the influence of the sheet until it is released by said grippers, and means carried by said frame members and having meshing relation with said racks for moving the arcuate member and the wheel bodily, longitudinally in the

path of the sheets, in accordance with the size of the sheet.

4. In a sheet delivery, the combination of mechanism for retarding sheets upon their release from the grippers of a sheet conveyor comprising, a shaft mounted for rotation above the path of the sheets; a brake shoe segment rotatably mounted on said shaft; a sheet control disc fixed to said shaft adjacent said segment, the periphery of said disc being substantially tangent to the path of the sheets and having a recess formed therein to clear said grippers, means interconnecting said disc with said segment including a compression spring for maintaining the relative angular positions of the disc and segment, drive means for rotating said disc and therewith said segment at reduced surface speed with respect to said conveyor, and a wheel mounted below the path of the sheets for coaction with said segment to engage and retard the sheets, said compression spring permitting said segment to advance relative to said disc and said wheel under progressively increasing tension until the leading edge of the sheet is released by said grippers:
